UNITED STATES PATENT OFFICE.

CARL J. VELEY, OF KALAMAZOO, MICHIGAN, ASSIGNOR TO COMSTOCK AUTOMATIC PUMP CO., OF COMSTOCK, MICHIGAN.

PRESSURE-REGULATOR.

1,214,978.

Specification of Letters Patent.

Patented Feb. 6, 1917.

Application filed February 10, 1916. Serial No. 77,541.

To all whom it may concern:

Be it known that I, CARL J. VELEY, a citizen of the United States, residing at Kalamazoo, Michigan, have invented certain new and useful Improvements in Pressure-Regulators, of which the following is a specification.

This invention relates to improvements in pressure regulators.

10 The main objects of my invention are:

First, to provide an improved pressure regulator or control device adapted to control a prime mover, such as a motor, by means of a switch or the like.

15 Second, to provide an improved pressure control device which is adapted to act to stop a motor when the pressure reaches one predetermined point and to act to start a motor when the pressure falls to another 20 predetermined point.

Third, to provide an improved pressure regulator which is comparatively simple in structure and one which is not likely to get out of repair in use and may be accurately 25 adjusted to operate at desired pressures.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing, forming a part of this specification, in which:

Figure I is a detail view, partially in vertical section, of a structure embodying 40 the features of my invention.

Fig. II is a detail horizontal section on a line corresponding to line 2—2 of Fig. I.

Fig. III is an enlarged detail horizontal section on a line corresponding to the 45 broken line 3—3 of Fig. I.

Fig. IV is a horizontal section through the diaphragm chamber on a line corresponding to the broken line 4—4 of Fig. I.

In the drawing similar reference characters refer to similar parts throughout the several views, and the sectional views are taken looking in the direction of the little arrows at the ends of the section lines.

Referring to the drawings, the dia- 55 phragm chamber, designated generally by

the numeral 1, is connected to the tank in which the pressure is to be regulated by the pipe 2. The diaphragm chamber 1 is formed of a bottom section 3 and a top section 4 connected by bolts 5. The dia- 60 phragm 6 is clamped between the sections.

The actuating rod 7 is provided with a disk-like foot or shoe which rests upon the diaphragm and has a stem 9 reciprocating in an opening 10 in the top section of the 65 casing and having a longitudinal bore 11 for the reduced end 12 of the actuating rod. On this reduced end is a collar 13 having a slot 14 at one side in which the inner end of the actuated lever 15 is disposed. 70 The lever 15 is pivoted at 16 on the upwardly projecting pivot ears 17 on the top section of the diaphragm casing.

Washers 18 are disposed above and below the collar, the lower washer constituting a 75 stop coacting with the diaphragm casing to limit the downward movement of the actuating rod 7.

An inner spring supporting member 19 is threaded upon the inner end of the actuating rod for adjustment thereon. An outer supporting member 20 is provided with a central hole so that the actuating member reciprocates therethrough. The outer support member 20 is supported in a fixed 80 relation by the rods 21 which are carried by the top section of the diaphragm chamber. These rods are arranged through the inner support member 19 supporting it against rotation so that when the actuating 85 rod is rotated the support member 19 is adjusted thereon. The outer end of the rod is flattened at 22 to receive a wrench for convenience in adjusting the inner member. 90

A coiled spring 23 is arranged between these support members preferably to embrace the rods 21. The outer end of the spring being supported by the rods it acts against the pressure on the diaphragm and 100 its tension is, as explained, regulated by the turning of the rod.

A second spring 24 is arranged on the actuating rod with its inner end resting upon the outer support member 20, its outer 105 end engaging the adjusting nut 25 threaded upon the actuating rod. This spring tends to counteract the spring 23 and act with the pressure on the downward movement thereof as the pressure falls, thus securing 110

a variation between the high and low pressure actuations governed by the tension of the spring 24.

In the structure illustrated the actuated member 15 is connected through the arm 26 to the oscillating switch 27 shown conventionally in the switch box 28. The details of the switch are not shown as they form no part of my present invention.

10 I have illustrated and described my improvements in the form in which I have embodied the same in practice. I have not attempted to illustrate or describe certain modifications which I contemplate or 15 adaptations of my improved pressure regulator to devices other than electric switches, as I believe the disclosure made will enable the embodiment and adaptation of my improvements as uses and conditions 20 may require.

Having thus described my invention, what I claim as new and desire to secure by Letters Patent, is:

1. In a structure of the class described, the 25 combination of a diaphragm casing, a diaphragm in said casing, an actuating rod having a reduced inner end, its outer end being adapted to receive a wrench, a diaphragm engaging shoe for said actuating rod provided with a stem arranged to reciprocate in an opening in said casing and having a longitudinal bore receiving the reduced end of said actuating rod, a collar on the reduced end of said actuating rod having a slot at 30 one side thereof, washers above and below the collar, the lower washer being adapted to coact as a stop with said casing, an actuated member pivotally mounted on said casing with one end disposed in said slot in said 35 collar between said washers, a pair of spring support members, the inner member being threaded upon said actuating rod, said rod being movable through the outer member, supporting rods for the outer support member mounted on said casing, said inner member being slidable on said supporting rods, a coiled spring arranged between said support members arranged on said actuating rod with its inner end resting upon the outer 40 support member, and an adjusting member for said second spring threaded upon said actuating rod.

55 2. In a structure of the class described, the combination of a diaphragm casing, a diaphragm in said casing, an actuating rod having a reduced inner end, its outer end being adapted to receive a wrench, a diaphragm engaging shoe for said actuating rod provided with a stem arranged to reciprocate in an opening in said casing and having a longitudinal bore receiving the reduced end of said actuating rod, an actuated 60 member pivotally mounted on said casing

and operatively connected to said actuating rod, a pair of spring support members, the inner member being threaded upon said actuating rod, said rod being movable through the outer member, supporting rods for the outer support member mounted on said casing, said inner member being slidable on said supporting rods, a coiled spring arranged between said support members, a coiled spring of less strength than the spring arranged between said support members arranged on said actuating rod with its inner end resting upon the outer support member, and an adjusting member for said second spring threaded upon said actuating rod. 70 75

3. In a structure of the class described, the combination of a diaphragm casing, a diaphragm in said casing, an actuating rod having a reduced inner end, its outer end being adapted to receive a wrench, a diaphragm engaging shoe for said actuating rod provided with a stem arranged to reciprocate in an opening in said casing and having a longitudinal bore receiving the reduced end of said actuating rod, an actuated member pivotally mounted on said casing and operatively connected to said actuating rod, a pair of spring support members, the inner member being threaded upon said actuating rod, said rod being movable through the outer member, supporting rods for the outer support member mounted on said casing, said inner member being slidable on said supporting rods, a coiled spring arranged between said support members, a coiled spring of less strength than the spring arranged between said support members arranged on said actuating rod with its inner end resting upon the outer support member, and an adjusting member for said second spring threaded upon said actuating rod. 80 85 90

4. In a structure of the class described, the combination of a diaphragm casing, a diaphragm in said casing, an actuating rod having a reduced inner end, its outer end being adapted to receive a wrench, a diaphragm engaging shoe for said actuating rod provided with a stem arranged to reciprocate in an opening in said casing and having a longitudinal bore receiving the reduced end of said actuating rod, a collar on the reduced end of said actuating rod having a slot at one side thereof, washers above and below the collar, the lower washer being adapted to coact as a stop with said casing, an actuated member pivotally mounted on said casing with one end disposed in said slot in said collar between said washers, a pair of spring support members, the inner member being threaded upon said actuating rod, said rod being movable through the outer member, supporting rods for the outer support member mounted on said casing, 100 105 110 115 120 125

- said inner member being slidable on said supporting rods, and a coiled spring arranged between said support members.
5. In a structure of the class described, the combination of a diaphragm casing, a diaphragm in said casing, an actuating rod having a reduced inner end, its outer end being adapted to receive a wrench, a diaphragm engaging shoe for said actuating rod 10 provided with a stem arranged to reciprocate in an opening in said casing and having a longitudinal bore receiving the reduced end of said actuating rod, an actuated member pivotally mounted on said casing 15 and operatively connected to said actuating rod, a pair of spring support members, the inner member being threaded upon said actuating rod, said rod being movable through the outer member, supporting rods for the 20 outer support member mounted on said casing, said inner member being slidable on said supporting rods, and a coiled spring arranged between said support members.
6. In a structure of the class described, 25 the combination of a diaphragm casing, a diaphragm in said casing, an actuating rod adapted to receive a wrench at its outer end, its inner end being operatively associated with said diaphragm, a pair of spring support members, the inner member being threaded upon said actuating rod, said rod being movable through the outer member, supporting rods for the outer support member mounted on said casing, said inner member being slidable on said supporting rods, whereby when said actuating rod is rotated 30 said inner support is adjusted thereon, a coiled spring arranged between said support members, a coiled spring of less strength than the spring arranged between said support members, arranged on said actuating rod with its inner end supported by the 35

outer support member, and an adjusting member for said second spring threaded upon said actuating rod. 45

7. In a structure of the class described, the combination of a diaphragm casing, a diaphragm in said casing, an actuating rod adapted to receive a wrench at its outer end, its inner end being operatively associated with said diaphragm, a pair of spring support members, the inner member being threaded upon said actuating rod, said rod being movable through the outer member, supporting rods for the outer support member mounted on said casing, said inner member being slidable on said supporting rods, whereby when said actuating rod is rotated said inner support is adjusted thereon, and a coiled spring arranged between said support members. 50 55 60

8. In a structure of the class described, the combination of a diaphragm casing, a diaphragm in said casing, an actuating rod operatively associated with said diaphragm, 65 a pair of spring support members, the outer member being relatively fixed, the inner member being adjustable upon said actuating rod, said rod being movable through the outer member, a coiled spring arranged 70 between said support members, a coiled spring of less strength than the spring arranged between said support members, arranged on said actuating rod with its inner end supported by the outer support member, 75 and an adjusting member for said second spring threaded upon said actuating rod.

In witness whereof, I have hereunto set my hand and seal in the presence of two witnesses.
